United States Patent Office

Des. 186,754
Patented Nov. 24, 1959

186,754

WALLET

Paul T. Poutinen, Broward County, Fla.

Application June 8, 1959, Serial No. 56,273

Term of patent 7 years

(Cl. D87—3)

FIG. 1 FIG. 2 FIG. 3

FIG. 4

Fig. 1 is a top plan view of a wallet, showing my new design.

Fig. 2 is a side elevational view thereof.

Fig. 3 is a bottom plan view thereof.

Fig. 4 is a perspective view of the wallet in open condition, parts being turned back.

The essential features of the design are shown in full lines.

I claim:

The ornamental design for a wallet, as shown and described.
